APPARATUS FOR TESTING OIL WELLS

Thomas Belmont Losey, Jr., Houston, Tex.

Application February 15, 1938, Serial No. 190,645

10 Claims. (CL. 166—1)

This invention relates to an apparatus for testing for oil, water, salt water, gas or cement shut-offs on casings.

An object of the invention is the provision of an apparatus for testing oil wells which is so constructed that a pair of valves including a sleeve valve are adapted to control communication between the string of pipe and the oil to be tested with one of the valves being operated by the sleeve valve and in accordance with the vertical movement of the string of pipe, cooperating means being employed for maintaining the valves closed until the string is rotated to permit the sleeve valve to move into contact with an operating stem of the other valve.

Another object of the invention is the provision of an apparatus for obtaining tests from wells in which a poppet valve is operated by a sleeve valve, the sleeve valve being so constructed and arranged that said sleeve valve gives a positive closure at all times.

A further object of the invention is the provision of an apparatus for testing wells in which a pressure piston is employed with the hydrostatic head of the drilling fluid acting on said piston for overbalancing the normal tendency of the closed tester case to float upwardly on a mandrel included in the apparatus, thus permitting the tool to be run into the hole without opening the valves. Therefore the weight necessary to push the mandrel down against the differential pressure is proportional to the amount of pipe in the hole at any particular depth.

A still further object of the invention is the provision of an apparatus for testing wells in which is included a pressure piston and a mandrel having integrally formed cams which will lock a sleeve valve against complete displacement and thus prevent accidental opening of a pipe line within the well.

Another object of the invention is the provision of an apparatus for testing oil wells in which cams are employed for preventing accidental operation of a sleeve valve, the cams being formed integrally with a piston adapted to be restrained or controlled by a pressure differential between the hydrostatic head of the drilling fluid and the atmospheric pressure in a pipe line in which the piston is operated, the sleeve valve being carried by the piston and being moved to an open or closed position by the reciprocation of said piston.

Another object of the invention is the provision of an apparatus for testing oil wells which has a pressure piston with conduits in the barrel of the piston cylinder for continuously supplying a hydrostatic head of the drilling fluid to the bottom of the piston, said piston having a passage-way for applying low pressure down to atmospheric from the inside of the string of pipe to

above the piston. Test strings are not always run completely empty as a short cushioning column of water is sometimes run.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a view in elevation of my tester shown with a rat hole packer seated on a shoulder within a well, and

Figure 2 is a vertical longitudinal section of the tester shown in Fig. 1.

Referring more particularly to the drawing, 2 indicates the lower end of a string of pipe which is connected to a main mandrel 5 by threads 4 and a sleeve 3. This mandrel is provided with a longitudinal passage 6. The string of pipe extends upwardly and is of the well known type used in well holes 1.

A wiper ring 7 is mounted in an angular groove formed at the inner periphery of a packing gland nut 8 and embraces the mandrel 5. This nut is also provided with an annular chamber 9 embracing the mandrel 5 and is adapted to be packed with grease or other material for lubricating the outer wall of said mandrel.

A sleeve 11 embraces the mandrel 5 below the nut 8 and has threaded connection at 9 with the nut. This sleeve below the lower end of the nut is provided with an annular channel around the outer wall of the mandrel 5 and receives a packing 10 which is in close contact with said mandrel.

The mandrel is provided with an enlargement forming a piston 5^a which is received within the sleeve 11 and the inner diameter of the sleeve at this point is enlarged to receive said piston. This enlarged chamber in the sleeve 11 forms a shoulder which is adapted to be abutted by the upper end of the piston 5^a as is clearly shown in Figure 2.

The sleeve 11 has an annular channel 14 embracing the piston 5^a and this channel is adapted to be packed with grease which is forced through a threaded opening in the side wall of the sleeve 11 and normally closed by a plug 14^a.

The piston per se is provided with a plurality of cam slots 13 formed in the side walls thereof and these slots are of such a configuration that the portion 13^a forms cams which are adapted to receive pins 15 which are screwed into openings 15^a in the side walls of the sleeve 11. The inner ends of these pins project into an enlarged portion 15^c of the slots so that they may be engaged beneath the portions 13^b for a purpose

which will be presently explained. These slots have a restricted vertical portion opening above the piston 5^a.

Below the slots 13 in the piston 5^a said piston 5 is reduced in diameter and the packing 16^a embraces the reduced portion of the piston and is located between the reduced portion and a liner 17 received by the inner wall of the sleeve 11. This liner is held in place between a shoulder 41 on the sleeve 11 and by the upper end of a threaded nipple 22 which is screwed into the lower internally threaded end of the sleeve 11.

A disc 18 is mounted at the lower end of the reduced portion 16 of the piston 5^a and is held 15 in place by a shoulder on the upper end of a sleeve valve 19 which is threaded into the lower reduced portion 16 of the piston 5^a. Thus, it will be seen that the disc 18 which is in sliding contact with the liner 17 is moved directly with the piston 5^a and since this disc holds a packing 16^a 20 in position said packing is likewise moved with the piston.

The mandrel 5 is provided with radial passages 12 which supply the lower pressure in the passage 6 to the upper side of the upper end of the pressure piston 5^a. This pressure is contained in 25 the region covered by the packing 16^a less the region carried by the packing 10. The nipple 22^a has an annular enlargement intermediate its ends 30 to form a pair of oppositely disposed shoulders with the upper shoulder engaging the lower end of the sleeve 11 when the nipple is screwed into position on said sleeve. The nipple 22 is provided with radial passages 24 and the inner ends of 35 these passages are in communication with vertically disposed passages 23 which lead from the exterior of the nipple 22 and likewise the sleeve 11 to a chamber 37 formed by the liner 17, the disc 18 and the upper end of the nipple 22. When 40 a test is to be made the mandrel 5 is rotated until the pins 15 are in alignment with the vertical portions of the slots 14 and the piston 5^a will descend. The fluid pressure from the exterior of the sleeve 11 acting on the disc 18 through the 45 passages 23 and 24 will cushion the descent of the piston as is evident.

A passage 36 formed longitudinally of the sleeve valve 19 extends from the extreme lower end of the valve to the upper end and is in communication with the longitudinal passage 6 in the mandrel 5.

A nut 20 embraces the sleeve valve 19 and is threaded into the upper end of the nipple 22 and compresses a packing 21 positioned in an annular pocket or chamber in the nipple and embracing the sleeve valve.

A packing 25 is also positioned in an annular pocket in the nipple 22 and adjacent the lower end of the sleeve valve 19 when said valve is in 60 closed position. This packing is held in place by a packing gland ring 27 which is threaded into the lower end of the nipple.

A plug 26 is positioned in the passage 36 in the lower end of the sleeve valve 19 but may be forced out when desired by applying sufficient pressure within the sleeve valve 19 when said valve is in closed position as shown in Fig. 2. The sleeve valve is provided with a plurality of radial passages 23^a which are adapted to place the longitudinal passage 36 of the sleeve valve in communication with a chamber 27^a formed within the packing gland nut 27.

A valve stem 30 is slidably mounted in a valve body 31 at the central axis of said body and carries a valve 30^a at its lower end adapted to close

a chamber 32^a in the lower section 32 which is normally in communication with the fluids under high pressure in a well. A spring 29 has one end resting upon the top of the valve body 31 while the opposite end engages a nut 28 on the upper end of the stem 30 whereby the valve 30^a will be urged on its seat to close the passages 34 in the valve body 31. These passages when the valve 30^a is open connect the chamber 32^a with the chamber 35. It will be noted that when the lower end of the sleeve valve 19 is lowered sufficiently it will engage the nut 28 at the upper end of the valve stem 30 and force the nut and valve stem downwardly for opening the valve 30^a to allow fluid from the chamber 32^a to pass upwardly through the passages 34 and thence through the passage 36 into the passage 6 in the mandrel 5.

The lower end of the section 32 is provided with threads 33 to receive any type of pack off. Fig. 20 1 illustrates my tool with rat-hole pack-off 38. A perforated tube 39 descends below the packer element and has its lower end closed so that the test fluids or gases entering the testing apparatus 25 will in effect be screened.

Figure 1 illustrates the rat hole type pack-off. The tool, however, may be run with any type of pack-off such as a casing, open hole, cone packer or a combination.

The operation of my device is as follows: High 30 pressure fluid from the lower part 40 of the well will enter the perforated tube 39 and pass into the high pressure chamber 32^a below the poppet valve assembly 30^a and 31. The valve 30^a being on its seat by reason of the spring 29 together 35 with the fluid pressure on valve head 30^a will prevent the fluid from entering the low pressure chamber 35, the chamber 27^a and the passage 36 in the sleeve 19 after the apparatus has been let down into the well by means of a string of pipe 40 2 and the packer 38 seals the lower portion of the well below the packer from that portion of the well above the packer. Before the apparatus is placed in the well the mandrel 5 is so positioned with respect to the upper sleeve section 11 that 45 the pins 15 will be engaged beneath the cam members 13^a. These pins and likewise the cam members are spaced approximately 120° apart but there may be two or more cooperating pins and cams. Until the apparatus reaches the position 50 when the packer 38 seals the rat hole of the well the sleeve valve 19 will be maintained in the position shown in Fig. 2 and the pins engaging the cams 13^a will prevent downward movement of the mandrel 5, the piston 5^a and the sleeve valve 55 19 so that the passages 23^a will be closed since that portion of the wall of the sleeve valve in which the passages are formed is in contact with the inner walls of the member 22^a. The plug 26 is maintained in position at the lower end of the 60 passage 36.

When it is desired to obtain a test it is only necessary to relieve part of the weight from the cam ledge 13^a resting on the pins 15 and to rotate the mandrel 5 through a predetermined arc 65 5 whence the pins 15 will move to the vertical portions of the cam slots 13 whereby the mandrel 5 will be released and it will move downwardly carrying the sleeve 19 downwardly whereby the passages 23^a will be open to the chamber 27^a.

After the sleeve valve 19 is opened the bottom 70 of said valve will move into engagement with the nut 28 on the stem 30 and force the valve 30^a off its seat at the underface of the valve body 31. Fluid in the high pressure chamber 32^a will enter 75

the chamber 35 through the passages 34 communicating with the chambers 27a and 35 and openable and closable by valve 30a. When the mandrel 5 is lowered and the ports 24a are opened to the chamber 27a a low pressure (approximately atmospheric) will be maintained in the chamber 27a and likewise the chamber 35 so that when the high pressure fluid enters these chambers when the valve 30a is opened the high pressure fluid will readily rise in the passage 36 in the valve 19 and enter the central passage in the string of pipe 2.

The tester is run into the hole on a string of pipe until the packer 38 reaches its seat and sufficient weight is placed on the packer to maintain it firmly on its seat. In applying weight on the packer, the mandrel 5 is moved downwardly until the safety catches at the underface of the cams 13a engage the pins 15 but the cams prevent the mandrel from opening the valve 19 and likewise the poppet valve 30a. When the parts are in the position placing the high pressure chamber 32a in communication with the passage in the string of pipe 2 the well will flow until the pressures are equalized or the tool is picked up and closed.

Raising of the drill stem or tubing allows the mandrel, piston and sleeve valve rod to come up and rotate into their uppermost position, so that the spring 29 may close the poppet valve 30a first, and then the sleeve valve 19. When it is assured that the tool is closed the packer 38 may then be pulled loose and the assembly withdrawn, thereby bringing up an uncontaminated sample from the formation tested.

During the movement of the mandrel assembly downwardly, forces are more or less balanced by the head of the fluid in the hole acting through ports 24, passages 23 and the chamber 37 under the disc 18 which forms the bottom of the piston 5a. Moving the piston downwardly forces the drilling fluid back through these ports to cushion the travel of the piston and likewise the mandrel which is formed integrally with the piston. Thus it will be seen that a sudden dropping of the drill stem when the packer is stuck or reaches its seat does not throw all of the load on the pins 15. The upward movement is cushioned by a reversal of these operations. It will be seen that a hydrostatic head is maintained through the middle of the device under the piston 5a while the low pressure acts above the piston and deviates the forces in a manner to counteract the normal tendency of the closed sleeve tester to be forced upwardly upon the drill stem mandrel and thus be incapable of sliding up and down within the sleeve 17. It will be seen that the tool may be balanced in this manner or overbalanced to hold down the housing which is formed by the sleeves 11 and 32 and in practice this case is held down in relation to the mandrel. The degree of overbalancing accomplished by this arrangement removes part of the drill stem load from the pin 15 which can be computed by multiplying the differential area by the pressure head.

It will also be seen that the cam grooves 13 are formed in an enlargement of the mandrel 5 which constitutes the piston 5a. This piston is thoroughly lubricated by lubricant which is stored in the annular chamber 14 and which has been forced from the chamber by the inward movement of the plug 14a.

The member 26 is pressed into the lower end 75 of the sleeve valve 19 for frictional engagement

with the countersunk pocket formed at the lower end of the passage 36 and the member 26 may be forced from this position when desired. A circulation may be maintained downwardly when the plug 26 is pumped out or the tool is opened. 5

The three main packings 10, 16a and 21 have the same differential pressure across them at all times.

The testing tool assembly composed of the tool proper, a pack-off, consisting of casing packer, 10 open hole packer or cone packer, or combination of these packers with a section of perforation is run in the hole on successive stands of drill pipe or tubing. When the pack-off is at the desired depth it is tripped or seated and the tool opened. 15 A blowing noise coming through the drill stem or tubing indicates fluid or gas coming in through the tool below. Should the drilling fluid recede the tool should be raised and then closed as this indicates the packer is not holding. It must be 20 borne in mind that when this tester is placed in the hole with an empty string that atmospheric pressure is placed on the formation to be tested by the various instrumentalities described above. 25

I claim:

1. An apparatus for testing a well hole and adapted for attachment to a string of pipe comprising a hollow body, a combined hollow mandrel and piston attachable to the string and slideable in the body, a push rod connected to the piston and including a sleeve valve closed at its lower end, a spring-pressed poppet valve in the body and engaged by the rod to open said poppet valve when the piston descends, the sleeve valve having ports normally closed by the body but 30 opened when the piston descends, and releasable cooperating means on the body and piston engageable for retaining the piston and valve against movement to maintain the sleeve valve closed, said cooperating means being releasable 35 to permit movement of the combined mandrel and piston to open the sleeve valve and poppet valve.

2. An apparatus for testing a well hole and adapted for attachment to a string of pipe comprising a hollow body, a combined mandrel and piston slidable in the body, a push rod connected to the piston and including a sleeve valve, a spring-pressed poppet valve in the body and engaged by the rod to open said poppet valve when 45 the piston descends, the sleeve valve having ports normally closed by the body but opened when the piston descends, and releasable cooperating means on the body and piston engageable for retaining the piston and valve against movement 50 to maintain the sleeve valve closed, said cooperating means being releasable to permit movement of the combined mandrel and piston to open the sleeve valve and poppet valve, the body having a chamber below the piston and passages connecting 55 the chamber with high pressure fluid externally of the body.

3. An apparatus for testing a well hole and adapted for attachment to a string of pipe comprising a hollow body, a combined mandrel and piston slidable in the body, a push rod connected to the piston and including a sleeve valve, a spring-pressed poppet valve in the body and engaged by the rod to open said poppet valve when the piston descends, the sleeve valve having ports 60 normally closed by the body but opened when the piston descends, and releasable cooperating means on the body and piston engageable for retaining the piston and valve against movement 65 to maintain the sleeve valve closed, said cooperating means being releasable to permit movement of the combined mandrel and piston to open the sleeve valve and poppet valve, the body having a chamber below the piston and passages connecting 70 the chamber with high pressure fluid externally of the body.

75

- ing means being releasable to permit movement of the combined mandrel and piston to open the sleeve valve and poppet valve, the body having a chamber above the piston in communication with the string of pipe, the sleeve valve being in communication with the string of pipe and adapted to place said chamber in communication with the string of pipe when the sleeve valve is opened.
4. An apparatus for testing a well hole and adapted for attachment to a string of pipe, comprising a hollow body, a hollow mandrel reciprocally mounted within the body, a sleeve valve closed at its lower end and carried by the mandrel, a normally closed poppet valve in the body and actuatable by the sleeve valve to open position, cooperating means between the body and mandrel for retaining said mandrel and sleeve valve against reciprocating movement to prevent opening of said sleeve valve, said cooperating means being releasable to permit movement of the mandrel and sleeve valve to open said valve while permitting the mandrel to be lowered sufficiently to cause the sleeve valve to open the poppet valve, said sleeve valve having closable and openable ports for relieving pressure on the oil to be tested so that the oil will flow through the string of pipe.
5. An apparatus for testing a well hole and adapted for attachment to a string of pipe comprising a hollow body, a hollow mandrel mounted for reciprocation within the body, a sleeve valve closed at its lower end and carried by the mandrel for placing the lower end of the body in communication with atmospheric pressure but normally maintaining the mandrel closed, a normally closed poppet valve in the lower end of the body and actuatable by the sleeve valve to open position, means for retaining said mandrel and sleeve valve against reciprocating movement to prevent opening of the poppet valve, said retaining means being releasable to permit the mandrel and sleeve valve to move downwardly sufficiently to open said poppet valve, the body being provided with a chamber between the valves, the sleeve valve being in open communication with the hollow mandrel, said sleeve valve having closable and openable ports for placing said chamber in communication with the hollow mandrel.
6. An apparatus for testing a well hole and adapted for attachment to a string of pipe comprising a hollow body, a hollow mandrel mounted for reciprocation within the body, a piston connected to the mandrel and provided with cams, pins on the body cooperating with the cams for retaining the mandrel and piston in a predetermined elevated position in the body, a valve carried by the piston and provided with closable and openable ports, a sleeve embracing the valve when it is in uppermost position and adapted to close the ports, a poppet valve and cage dividing the lower part of the body into high and low compression chambers, release of the cams from the pins permitting said first valve to be moved by the piston to open the second valve and to place the low compression chamber in communication with the string of pipe.
7. An apparatus for testing a well hole and adapted for attachment to a string of pipe comprising a hollow body, a hollow mandrel mounted for reciprocation within the body, a piston connected to the mandrel and provided with cams, pins on the body cooperating with the cams for retaining the mandrel and piston in an elevated inoperative position in the body, a valve carried by the piston and provided with closable and openable ports, a sleeve embracing the valve when it is in uppermost position and adapted to close the ports, a valve and cage dividing the lower part of the body into high and low compression chambers and operated to open position by the first valve, release of the cams from the pins permitting said first valve to be moved by the piston to open the second valve, said body being provided with passages for directing fluid under pressure beneath the piston.
8. An apparatus for testing a well hole and adapted for attachment to a string of pipe, comprising a hollow body, a hollow mandrel reciprocally mounted within the body, a sleeve valve carried by the mandrel, a normally closed valve in the body and actuatable by the sleeve valve to open position, cooperating means between the body and mandrel for retaining said mandrel and sleeve valve against reciprocating movement to prevent opening of the second valve, said retaining means being releasable to permit the mandrel and sleeve valve to be lowered sufficiently to cause the sleeve valve to open the second valve, said sleeve having closable and openable ports for relieving pressure on the oil to be tested so that the oil will flow through the string of pipe, the sleeve valve having the lower end open, a plug closing said end and adapted to be pumped out when desired.
9. An apparatus for testing a well hole and adapted for attachment to a string of pipe, comprising a hollow body, a hollow mandrel reciprocally mounted within the body, a sleeve valve carried by the mandrel and opening into the string of pipe, a normally closed valve in the body and actuatable by the sleeve valve to open position, cooperating means between the body and mandrel for retaining the mandrel and sleeve valve against movement to prevent opening of the said valve, said retaining means being releasable to permit the mandrel and sleeve valve to be lowered to cause the sleeve valve to open the second valve, said sleeve having closable and openable ports for relieving pressure on the oil to be tested so that the oil will flow through the string of pipe, and means for cushioning the movement of the mandrel.
10. An apparatus for testing a well hole and adapted for attachment to a string of pipe, comprising a body, a hollow mandrel reciprocally mounted within the body, a sleeve valve carried by the mandrel and opening into the string of pipe, a normally closed valve in the body and actuatable by the sleeve valve to open position, cooperating means between the body and mandrel for retaining the mandrel and sleeve valve against movement to prevent opening of the second valve, said retaining means being releasable to permit the mandrel and sleeve valve to be lowered to cause the sleeve valve to open the second valve, said sleeve having closable and openable ports for relieving pressure on the oil to be tested so that the oil will flow through the string of pipe, a piston connected to the mandrel, and means for creating different pressures on the piston for cushioning the piston and mandrel during vertical movement.

THOMAS B. LOSEY, JR.
